UNITED STATES PATENT OFFICE.

JULIUS H. HOLMGREEN AND RICHARD J. HOLMGREEN, OF SAN ANTONIO, TEXAS, AS
SIGNORS TO ALAMO IRON WORKS, OF SAN ANTONIO, TEXAS, A CORPORATION OF
TEXAS.

ROTARY WELL-DRILLING MACHINE.

Application filed June 23, 1923. Serial No. 647,384.

Our invention relates to a rotary well drilling machine such as is used in drilling oil wells and the like and it is an object of the invention to provide a machine of the character described which shall be very strong and compact, which shall consist of relatively few parts and which shall not be liable to get out of order.

Another object of the invention is to provide guiding means for the rotating table which shall be in elevated position for securing and maintaining stability in the table and which shall also prevent the table from being thrown upward.

15 A further object of the invention is to provide disappearing handles for the drive collar and the slip ring.

Still another object is to provide a simple and effective automatic shaft lock to hold the shaft from rotation when the clutch is out of engagement and automatically release it when thrown in.

20 A further object is to provide an improved method of fastening the driving pinion for the table to its shaft.

Still another object is to provide an improved driving collar and in connection therewith an improved method of welding a steel driving lug to the iron collar.

25 Still another object is to provide improved lubricating means for the device and various other improvements in details and arrangement of parts will appear hereinafter.

Referring to the accompanying drawings, which are made a part hereof and on which similar reference characters indicate similar parts,

Figure 1 is a perspective of our device,

Figure 2, a side elevation,

40 Figure 3, a longitudinal section on line 3-3 of Figure 1,

Figure 4, a transverse section on line 4-4 of Figure 1,

45 Figure 5, a transverse section on line 5-5 of Figure 1,

Figure 6, a transverse section on line 6-6 of Figure 1,

Figure 7, a transverse section on line 7-7 of Figure 1,

50 Figure 8, a fragmentary perspective of the shaft lock and operating mechanism therefor, also shown in Figures 1, 2 and 5,

Figure 9, a perspective of the table, the slip ring and the driving collar in disassembled relation, and

Figure 10, a detail of slips for seizing the drill stem and holding the same while other sections are connected thereto or disconnected therefrom.

55 In the drawings reference character 20 denotes a base mounted on and secured to timbers 21 by means of bolts 22 or in any preferred manner. Lugs 23 extend downward from the base and bear against the inner sides of the timbers to hold the parts in place. The base is provided with a central opening and an annular flange 24 surrounds the opening and rises above the upper part of said flange being flared outward to provide a seat for tapered roller bearings 25 60 and the seat being provided at its outer periphery with a substantially vertical annular flange 26 to limit the outward movement of the rollers. About the circumference of the base there are located a series (here 70 shown as four in number) of upright posts 27 for supporting the split ring 28 which provides an outer bearing for a rotary table 29 resting on the rollers 25.

65 The ring is split and provided at opposite sides of the table at 30 with ears secured together by bolts 30'. Each half of the split ring rests on two of the posts 27 and is or may be provided with downwardly extending lugs to engage in seats in the tops of 75 the posts to insure correct positioning of the ring. The split ring and the posts have openings to receive bolts 31 for holding the parts together.

70 The rotating table consists essentially of upper and lower disks connected by an outer wall 32 (Fig. 4), each disk having a large central opening and the two being joined adjacent the opening by vertical pillars 33 and by the metal surrounding the openings 85 at 34 and 35 in the table (Fig. 1). A depending flange 36 on the table fits within the flange 24 of the base and securely closes the race for the antifriction rollers against the entry of mud and slush from the well hole, 90 besides contributing to the stability of the structure and helping to maintain the table in correct position. A depending flange 37 on the table (Fig. 4) bears against the outer ends of the rollers 25 in cooperating relation 100 with the flange 26. A horizontal flange 38 bears against the underside of the split ring to prevent tilting of the table. A set of gear teeth 39 is provided between the last two flanges referred to. The upper disk of the 105

table is extended beyond the outer face of the connecting wall 32 and is cored out at 40 to provide an oil groove for distributing oil about the contacting faces of the table 5 and the split ring. An oil cup 41 on the ring (Fig. 3) communicates with the groove 40 by means of a passage through the wall of the ring and an oil groove in the outer face of the table indicated at 42 in Figure 3 and 10 extending upward at an angle of approximately 15 degrees to distribute the oil over the face of the ring by capillary attraction and the relative rotation of the parts. The oil cup has a lid 41' and a drainage opening closed by a plug 42'.

The upper surface of the table is provided with openings 34 and 35 adapted to receive respectively a post 43 for driving the grief stem clamp and a rotary wrench post 44. 20 These holes extend down into the lower disk of the table in order to hold the parts referred to securely and are duplicated at each side of the table for convenience in operation. Coacting with the wrench post 44 is 25 a standing wrench post 45 having its lower end located in a socket 46 on a projecting part of the post. A flange 47 extends from each side of the socket to the adjacent post 27 to make the connection between the socket 30 and the base rigid and secure.

The table as heretofore explained has a central opening in which is received a split slip ring 48 consisting of two duplicate halves. In the present embodiment we have 35 shown these halves as unconnected but any convenient or desirable means may be provided for fastening them together in working relation. The slip ring has a vertical upper bearing surface at 49 resting against a similar surface at 50 on the table and a flange 51 resting on the lower disk of the table above the annulus 36, said slip ring having a circular part projecting downward and bearing against the inside of said annulus. 40 In this way a very steady and secure support is provided for the slip ring. To prevent upward movement of the slip ring at undesired times the table is provided with oppositely located L-shaped slots 52 which 45 extend down through the upper disk and then branch in one direction below said disk. These slots receive lugs 53 on the respective halves of the slip ring said lugs passing down through the vertical part of their respective slots and then to the right, as shown. 50

For the purpose of lifting the slip ring out of its seat on the table we have provided each half with a handle 54 here shown as having a form of a hook. A cavity is provided in the upper face of each slip ring section in which the hooks normally lie when not in use, the cavities being deep enough to bring the hooks below the surface of the slip ring. Each of the hooks has a 55 pivot pin 55 by means of which it may be

readily removed or replaced. The slip ring may be reduced exteriorly between the face 49 and the flange 51 and may be provided with vertical flanges 55' for strengthening the ring without unduly adding to the weight thereof.

The inner face of the slip-ring is conical and is adapted to receive slips for gripping the stem of the drill to sustain the string while adding or removing sections. Such 75 slips are shown in Figure 10 at 56 and are preferably three in number, the three when in place filling the space between the slip ring and the stem to be supported. The outer face of the combined slips forms a frustum of a cone adapted to fit in the frusto-conical interior of the slip-ring and each slip has hardened transverse corrugations or teeth at 57 on its inner face to afford a secure gripping action, the body of the slip being relatively 80 soft. The dimensions of the slips are such that a line drawn from 58 to 59, i. e. at the greatest diameter of the slip, will be longer than the diameter of the central opening of the slip ring at its lower end. The purpose of this is to prevent any chance of a slip being dropped and falling through the central cavity of the slip-ring into the well. With the dimensions indicated the slip is 85 bound to be caught in the slip ring. At 90 the upper end of each slip is a post 60 having threaded engagement with the slip and a handle 61 is pivoted to the post and serves as a means for handling the slip.

The slips are so constructed that the upper ends will lie in substantially the same plane with the upper surface of the rotating table. The same cavity in the slip-ring serves also to receive the grief stem clamp or driving collar comprising two identical 100 sections 62, the upper surface of which also is intended to lie exactly in the same plane as the upper surface of the slip-ring sections and of the rotating table. This collar has a central opening to receive and drive the "grief stem" of the drill while permitting free up and down movement thereof. Each slip-ring section has upper and lower collars 63 and 64 bearing against the inner face of the slip-ring and a lug 65 projecting from the surface between the collars engaging in an L-slot 66 of the corresponding slip-ring section. In our construction this lug is made of steel which is fixed to the iron of the driving collar by a method which insures that the lug will never break away from the body of the driving collar and at the same time enables us to utilize a cheap material for the body of the collar.

Each section of the collar is provided at 115 its upper end with a handle 67, here shown as substantially T-shaped, said handle being pivoted to the collar at the lower end of the stem 68. The handles lie in depressions in the upper ends of the collar sec- 120 125 130

- tions so as not to interrupt the smooth upper face of the rotating table and parts carried thereby. At its outer end each cross-piece of the T-shaped handles extends beyond the 5 periphery of the collar section and into a slot in the slip-ring indicated at 69 in Figure 9. This helps to insure a positive driving connection between the slip-ring and the driving collar for the grief stem.
- 10 For driving the table we have provided a shaft 70 on which is loosely mounted a sprocket 71. This sprocket has clutch teeth at each side as clearly shown in Figures 1 and 2 and therefore is reversible so that as 15 the teeth at one side become worn or broken it may be reversed on the shaft and so give double service. A clutch member 72 is connected to the shaft for rotation therewith by diametrically opposed splines 73 (Figures 3 20 and 7) permitting it to slide on the shaft. This clutch member is also reversible in similar manner and for the same reasons as the sprocket 71. A clutch collar 74 is mounted in an annular slot of the clutch member 25 72 and a rockshaft 75 has arms 76 pivoted by means of screws 76' to opposite sides of the collar. An oil cup 77 at the top of the collar is connected by a passage to the groove for collar 74 in member 72 and said oil cup 30 has a lid 77' with lugs at the rear end projecting so as to engage lugs at the rear of the box to prevent the cover from tilting back so far as to remain open, whereby dirt and other foreign objects might enter the 35 oil holes. The rockshaft 75 has an upwardly projecting arm at each end for supporting an operating lever 78 for the clutch and it is journaled adjacent to said arms in bearings 79 fixed to the foundation timbers 21.
- 40 For locking the shaft 70 against rotation when the clutch is disengaged we have provided a stop collar 80 fixed to the shaft, this collar having a series of openings in its periphery to receive a lug 81 at the end of a latch 82 (Fig. 8) pivoted on a bracket 83 secured to one of the timbers 21. A latch lifter 84 is pivotally secured to the lever 76 (Fig. 7) and has near its forward end a cam 85 acting against a lug 86 on the latch 82.
- 45 Another lug 87 on the latch limits its backward movement and holds it in position out of a 55 tion below the upper level of the table. The lifter 84 has a notch at 88 on its underside which permits the lifter to fall after the clutch is fully thrown out as in Figure 2, whereupon the shaft lock 82 by its lug 81 engages one of the notches in the collar 80 and so locks the shaft against rotation. At other times the under surface of the lifter 60 rides on an upstanding flange of a fixed detent 89 said flange being provided at the rear end with a raised guiding lug 90 which helps to hold the sliding lifter in place. When the notch 88 engages with the detent 65 the clutch member 72 is locked out of action
- and cannot be returned without first positively lifting the clutch lifter out of engagement with the detent. This is done preferably by means of a foot lever 91, here shown as mounted on the same pivot 92 which supports the shaft lock 82. When the notch 88' is engaged the clutch member is locked in active position.
- The shaft 70 carries at its inner end a bevelled pinion 93 with teeth engaging the teeth 39 of the rotating table said teeth preferably being thicker than the teeth of the table to take care of the greater wear of the teeth on the pinion. A shroud 94 at the larger end of the pinion strengthens the teeth on the pinion and bears against the outer ends of those on the table. The pinion is secured to the shaft by a gib key and is pressed on the gib key only and not on the shaft, the gib being reversed as shown with its head at 75 the outer end of the pinion this being to prevent the shaft from working through the pinion under heavy duty and also making the pinion easily removable from its shaft when the shaft is dismounted.
- 80 The inner and outer bearings 96 and 97 for the shaft 70 are split at an angle to provide for ready dismounting and replacing of the shaft when the caps of the bearings are taken off. The inner bearing is located 85 midway between timbers 21 on a flange extending laterally from the base 20 and bolted to each of the said timbers, the lower part of the bearing being integral with the flange.
- 89 An oil cup 98 is located at one side of the bearing 96 and is integral therewith, said cup having a passage leading to the bearing. A lid 99 for the oil cup is pivoted at its inner rear corner and has a bent nose at 95 its forward end extending up under a lip 100 at 100 on the removable cap of the bearing which construction helps to exclude mud and slush from the oil cup. A lock for the oil cup cover comprises an inverted bolt 101 having its head extending downward into the oil cup to prevent swinging of the lid into open position and having an adjustable nut above the cover by which the position of the bolt can be determined. Preferably the head is conical in shape, flaring away 105 from the bolt as shown in Figure 6. The flaring head catches under an inwardly extending tapered ledge at the top of the cap and so holds the lid shut, movement of the lid toward open position pulling it down into tight engagement with the top of the box. The outer bearing 97 has a somewhat 110 similar oil cup closed by a pivoted lid 102 pivoted at 103.
- 115 It will be obvious to those skilled in the art that our device may be modified in various ways and therefore we do not limit ourselves to the specific means shown in the drawings and described in the specification, but only as indicated in the appended claims.

Having thus fully described our said invention, what we claim as new and desire to secure by Letters Patent, is:

1. In a well drilling machine, a rotary table, a split ring embracing the table and having a bearing surface in contact with a bearing surface on the table, and driving means for the table on its under side below the split ring, substantially as set forth. 70
2. In a well drilling machine, a rotary table having a bearing surface on its outer periphery, a split-ring embracing the table and having a bearing surface in contact with that of the table, driving means for the 75 table on its underside below the split ring, and a horizontal flange on the table between the ring and said driving means bearing against said ring, substantially as set forth. 80
3. In a well drilling machine, a rotary table having a bearing surface on its outer periphery, a split-ring embracing the table and having a bearing surface in contact with that of the table, driving means for the 85 table on its underside below the split ring, an annular recess in the outer face of the table at the upper edge of said ring, an oil reservoir on the ring, and an inclined passage between the ring and the table leading from the oil reservoir up to said recess, 90 substantially as set forth. 95
4. In a well drilling machine, a base embodying a race for anti-friction devices and a series of posts arranged about said race, anti-friction devices on the race, a rotating 100 table resting on the anti-friction devices, a ring bearing against the outer periphery of the table and fixed to said posts, and a horizontal flange on the table bearing against the underside of said ring, substantially as set forth. 105
5. In a well drilling machine, a rotating table, a fixed ring surrounding the table and having bearing engagement with the outer surface thereof, an overhanging flange at the 110 top of the table, and a recess for lubricant beneath said flange communicating with the bearing surfaces of the table and the ring, substantially as set forth. 115
6. In a well drilling machine, a base, a 120 rotary table having a bearing surface on its outer periphery, a split ring embracing the table and having a bearing surface in contact with said bearing surface on the table, fixed posts on the base supporting the split ring, and bolts passing up through said base said post and said ring for securing the ring in place, substantially as set forth. 125
7. In a drilling machine, a rotary table, a 130 split slip-ring supported centrally thereof, a split grief stem clamp supported centrally of the slip ring, handles on the independent segments of the slip-ring, independent handles for the separate segments of the grief stem clamp the upper faces of the table the slip-ring and the grief stem drive collar ly-

ing approximately in the same plane, and depressions in the upper faces of the slip-ring and the grief stem drive collar for receiving the handles when out of action whereby the table top formed by the combined parts remains flat, substantially as set forth. 70

8. In a drilling machine, a rotary table having a central opening, a split slip-ring supported in said central opening, a split grief stem drive collar supported in the central opening of the slip-ring, disappearing handles on each segment of the grief stem clamp, and projections on said handles engaging openings in the slip-ring, substantially as set forth. 75 80

9. In a well drilling machine, a rotating table, a slip-ring therefor having a circular axial opening, a split grief stem drive collar supported in said opening, and means for locking the segments of the grief stem drive 85 collar to the slip-ring, substantially as set forth. 90

10. In a well drilling machine, a rotary table having a central opening, undercut slots leading away from it, extending only partly around the inner periphery of the table, a split slip-ring mounted in said central opening, and lugs on the segments of the slip-ring engaging said undercut slots, substantially as set forth. 95 90

11. In a well drilling machine, a rotary table, a slip-ring on the table having a central opening, L-shaped slots leading therefrom, means for securing the slip-ring to the table, a split grief stem drive collar mounted in the opening of the slip-ring, and lugs on the grief stem drive collar engaging under the horizontal shoulder formed by said L-shaped slots, substantially as set forth. 105 100

12. In a drilling machine, a rotating table, a shaft geared thereto, means for driving the shaft including a clutch, a collar on the shaft having peripheral openings, a detent supported adjacent the shaft adapted to engage said openings, a lever for operating the clutch, and connections from the lever for disengaging the detent when the clutch is engaged, substantially as set forth. 110 115

13. In a drilling machine, a rotating table, a shaft geared thereto, means for driving the shaft including a clutch, a collar on the shaft having peripheral openings, a detent supported adjacent the shaft adapted to engage said openings, a lever for operating the clutch, and a bar pivoted to the lever and having cam engagement with the detent for moving it out of engagement with the collar when the clutch is engaged, substantially as set forth. 120 125

14. In a drilling machine, a rotating table, a shaft geared thereto, means for driving the shaft including a clutch, a collar on the shaft having peripheral openings, a detent supported adjacent the shaft adapted to 130

engage said openings, a lever for operating the clutch, and a bar pivoted to the lever, said bar having cam engagement with the 5 detent for moving it out of engagement with the collar when the clutch is engaged, substantially as set forth.

15. In a drilling machine, a rotating table, a shaft geared thereto, means for driving the shaft including a clutch, a collar on the 10 shaft having peripheral openings, a detent supported adjacent the shaft adapted to engage said openings, a lever for operating the clutch, a bar pivoted to the lever and having cam engagement with the detent for 15 moving it out of engagement with the collar when the clutch is engaged, means for engaging the bar to lock the clutch in idle position, and foot operated means for releasing the bar from such engagement, substantially as set forth.

16. In a drilling machine, a rotary table, a slip ring supported in an opening therein, one or more handles mounted in recesses on the slip ring, and a depression at the rear 25 side of each handle relative to the direction of rotation of the table, substantially as set forth.

17. In a drilling machine, a rotary table, a slip ring thereon, a grief stem collar on 30 the slip ring, recesses in the upper face of said collar, and handles pivotally mounted on the collar in front of said recesses, substantially as set forth.

18. In a well drilling machine, a rotary 35 table, means sustaining the weight of the table, means on the under side of the table for driving it, and a split ring having bear-

ing engagement with the periphery of the table beyond said driving means, substantially as set forth.

40

19. In a drilling machine, a rotary table, a driving shaft therefor, a clutch member on the shaft, a lever to move said member into and out of driving position, means movable with the lever to lock the clutch member in idle or driving position, and foot-operated means for disengaging said locking means, substantially as set forth.

45

20. In a drilling machine, a rotating table, a shaft geared thereto, means for driving the shaft including a clutch, a collar on the shaft having peripheral openings, a detent supported adjacent the shaft adapted to engage said openings, a lever for operating the clutch, a bar pivoted to the lever said bar having cam engagement with the detent for 50 moving it out of engagement with the collar when the clutch is engaged said lever being manually movable out of engagement with the collar, and means to support the detent in a position below the level of the tabletop, substantially as set forth.

55

21. In a drilling machine, a rotary table, a driving shaft for the table, a disconnectable driving means for the shaft, a shifter lever therefor, and a shaft lock operable independently of or automatically with said shift lever, substantially as set forth.

60

In witness whereof, we have hereunto set our hands at San Antonio, Texas, this 30th 65 day of May, A. D. nineteen hundred and twenty-three.

70

JULIUS H. HOLMGREEN.
RICHARD J. HOLMGREEN.
